GEM SETTING

Werner Doering, Springfield, N.J., assignor to Jabel Ring
Manufacturing Co., Irvington, N.J., a corporation of
New Jersey

Filed Dec. 22, 1960, Ser. No. 63,302

Term of patent 3½ years

(Cl. D45—1)

*Fig. 1.**Fig. 2.**Fig. 3.*FIG. 1 is a top plan view of a gem setting, showing my new design;

FIG. 2 is a front elevational view; and

FIG. 3 is a bottom view.

The broken-line showing of a gem stone is for illustrative purposes only.

I claim:

The new and ornamental design for a gem setting, substantially as shown and described.
